(57) **CLAIM**

The ornamental design for a grease collection for griddle, as shown and described.

DESCRIPTION

FIG. 1 is a front perspective view of a grease collection for griddle, showing our new design;

FIG. 2 is a bottom perspective view thereof;

FIG. 3 is a top perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines depict portions of the grease collector for griddle that form no part of the claim. The broken lines act as boundaries of the claim where they intersect claimed surfaces.
